2 Sheets-Sheet 2

Fig. 4.

UNITED STATES PATENT OFFICE.

FRANCISCO FABRICIO Y DÍAZ, OF SAGUA LA GRANDE, CUBA.

APPARATUS FOR RAISING VEHICLES.

Application filed October 16, 1922. Serial No. 595,013.

To all whom it may concern:

Be it known that I, FRANCISCO FABRICIO Y DÍAZ, a citizen of the Republic of Cuba, resident at Mendez Capote Street, No. 24, 5 at Sagua la Grande, Province of Santa Clara, Cuba, have invented a certain new and useful Apparatus for Raising Vehicles, of which the following is a specification.

This invention is an improved apparatus 10 for raising vehicles such as automobiles to enable them to be inspected or repaired from below; for supporting a vehicle in a tilted or inclined position when desired; and for also turning the vehicle when raised, for 15 inspection from all sides, and is especially adapted for use in automobile exhibition halls and in repair shops and garages.

With the above and other objects in view the invention consists in the construction, 20 combination and arrangement of devices hereinafter described and claimed.

In the accompanying drawings

Figure 1 is a plan of a vehicle raising apparatus constructed and arranged in accordance with this invention.

Figure 2 is a similar view of the same equipped for raising four vehicles simultaneously.

Figure 3 is a partial elevation of the same 30 showing so much of the apparatus as is above the floor.

Figure 4 is a vertical, longitudinal sectional view of the same on the plane indicated by the line 4—4 of Figure 1.

Figure 5 is a vertical transverse sectional view of the same on the plane indicated by the line 5—5 of Figure 2.

Figure 6 is a horizontal sectional view of the same on the plane indicated by the 40 line 6—6 of Figure 4.

Figure 7 is a similar view on the plane indicated by the line 7—7 of Figure 4.

Figure 8 is a detail plan of one of the lifting beams.

Figure 9 is a detail sectional view of said lifting beam and its elevating screw and connections.

Figure 10 is a detail perspective of one of the blocks.

Figure 11 is a detail perspective of one of the outer cross bars.

Figure 12 is a detail elevation of one of the adjustable inner cross bars.

Figure 13 is a detail perspective of one 55 of the standards.

Figure 14 is a similar view of one of the supplemental lifting beams.

Figure 15 is a detail sectional view showing a modification.

The floor level of an exhibition hall, 60 garage or repair shop is indicated at *a* and a pit which is preferably circular is indicated at *1* in the upper portion of the pit, diametrically contracted as shown and the floor is provided at points on opposite sides 65 of the pit with parallel recesses *b*.

Embedded in the wall of the pit at the contracted upper portion thereof is an annular plate *A* which is here shown as composed of four sections 2, 3, 4, 5 secured 70 together by bolts 6 and arranged in partial overlapping relation. The inner diameter of said plate is less than that of the contracted portion of the pit so that said plate overhangs the wall of the contracted portion of the pit as shown in Figure 4. A pair of parallel plates 7, 8 are arranged in 75 superposed relation with the plate 8 uppermost and bearing directly on the plate *A*. Said plates are secured together by bolts 9 and the lower plate 7 has a downwardly extending portion 7' and is also provided with internal gear teeth 39.

An annular plate 10 is arranged in a guideway which is formed between the 85 inner portions of the plates 7, 8 and is engaged between antifriction bearing balls 11 with which said plates are provided, the said bearing balls being here shown as mounted on axle bolts 20 and as being arranged in races 7'', 8'' with which said plates 7, 8 are respectively provided, the plate 10 being also provided with corresponding races 10' as shown. Said annular plate or ring 10 is a turntable and supporting ring and is provided with inwardly extending arms 13, 14, 15 and 16 and also with an inwardly extending arm 136 which is arranged between the arms 15, 16.

Vertically arranged lifting screws 17, 18, 19, 20 extend through and are respectively engaged in threaded openings in said arms 13, 14, 15, 16 and have their upper ends stepped as at 17' in bores in the under side of a pair of lifting beams 22, 23, and are also provided with flanges 17'' arranged in counterbores in said lifting beams, the latter being provided on their under sides with collars 24 which engage under said flanges and are secured to the beams by 110

100
105
110

screws 25. Hence the upper ends of the lifting screws are swivelly connected to the lifting beams. The lower ends of said lifting screws are swivelly connected to a parallel platform 21 which is arranged thus for vertical movement and is suspended by the lifting screws in the pit.

A horizontally arranged shaft 50 is mounted in bearings 51 on the platform 21 and is provided at its ends with bevel gears 52, 53 which are splined thereto and shiftable thereon. The diametrically oppositely arranged lifting screws 17, 19 are respectively provided with bevel gears 54, 55 for engagement respectively by the gears 52, 53. Said lifting screws 17, 18, 19, 20 are also respectively provided with sprocket wheels 56, 57, 58, 59 which are engaged and connected together by an endless chain 60. A tensioning sprocket wheel 61 for the chain is engaged therewith and is mounted for rotation on an arm 62 which is pivotally mounted at 62' on the platform and has at its free end a slot 62'' through which passes a wheel screw 63. By means of the wheel 61 and its connections above described the chain may be put under the required tension to cause all of the lifting screws to be simultaneously rotated, when one of them is rotated, as will be understood.

Shifting arms 68, 69 are respectively provided for the gears 52, 53. Said arms are connected together for simultaneous movement by a rod 70 and have their forks engaged respectively with circumferential grooves 67, 67' with which inwardly extending sleeve portions of said gears are provided as indicated in Figure 7. The pivot of the shifting arm 68 is indicated at 68a. That of the arm 69 is formed by a squared vertical shaft 71 which passes through a corresponding opening in said arm. Said shaft is mounted for rotation and passes below the platform 21 and has at its lower end a tappet arm 72. Said shaft extends upwardly and has its upper end mounted in a bearing in a plate 28 which is mounted for rotation on the inwardly extending flange of an annular plate 26 which is arranged together with the plate 28 at the floor level in the mouth of the pit, said annular plate 26 being supported by brackets 27 which are bolted thereto and to the plate 8. Said plate 28 has a circular central opening, forming a manhole, and in which is seated a removable plate 29. The plate 28 has hangers 30 depending therefrom provided with unthreaded openings through which the lifting screws extend.

A shaft 42 which is parallel with the shaft 50 is mounted in bearings 43 on the platform 21 and is provided with a pulley 44 which is connected by a belt 45 with a pul-

ley 46 on the shaft of a motor 47. Said motor is here shown as an electric motor but may be of any suitable type. Shaft 42 is also provided with a gear wheel 48 which engages a gear wheel 49 on the shaft 50 so that the latter shaft may be driven from the shaft 42. Said shaft 42 also has a splined shiftable bevel gear 41 which may be engaged with and disengaged from a bevel gear 40 on a vertical shaft 37. Said shaft 37 is mounted in suitable bearings in the platform and in the arm 136 of the annular plate 10 and is provided with a pinion 38 which engages the internal gear 39. The gear 41 may be shifted into or out of engagement with the gear 40 by a shifting arm 64 the fork of which is engaged with an annular groove in a sleeve extension of said gear 41 and the said shifting arm is mounted on a vertical shaft 65 which has bearings in the platform 21 and the plate 28. A hand wheel 66 is provided which may be engaged with either the upper end of the shaft 65 or the shaft 71 as may be required.

The cover plate 28 has depending arms 75 which are secured by pins 76 to the arms 13, 14, 15, 16 of the plate or turntable element 10, thereby securing said cover plate in place and for rotation with said element 10.

The platform 21 has a vertical reversing element 74 the upper and lower ends of which are inclined to form cam surfaces 74' arranged to respectively engage the reversing arms 72, 73 of the shaft 71 at the limits of the vertical movement of the platform and its connections. The ends of the lifting pins 22, 23 are provided respectively with forks 22', 23' to receive the inner ends of extension beams 32, 33, said extension beams being connected to said lifting beams by pivoting bolts 32' and also by removable bolts 32a. Said extension beams also have inclined adjustable openings 32b and 32c, and near their outer ends vertical openings 34''. The outer ends of the extension pins 32 are connected together by detachable cross bars 34 which are provided at their ends with depending pins 34'' to enter the openings 34''' and at their centers with openings 34' forming eyes to facilitate the addition of weights of any kind other than vehicles which it may be desired to raise or lower by my improve apparatus. Said extension beams 32 are also connected together in pairs by adjustable cross bars 35 which have grooves 35' on their undersides at their ends to receive said beams.

Blocks 36 having recesses 36' in their upper sides to fit under the axles of an automobile are provided in their under sides with grooves 36'' to fit on the extension beams 32 and are further provided with inclined pins 36''' to enter appropriate openings 32b and thereby secure said blocks at any desired distance apart on said beams ac-

cording to the length of the vehicles to be raised or lowered and the corresponding distance between their axles.

When it is desired to raise four automobiles simultaneously I also employ a pair of supplemental lifting beams 79 which are arranged to bear on the beams 22, 23 and to be secured thereto by hooks 80. Said supplemental beams have forks 79' at their ends 10 which receive the inner ends of extension beams 81, 82, which extension beams are connected to the supplemental beams by pivoting bolts and by removable bolts such as heretofore described in connection with the beams 22, 23 and extension beams 32, 33. The outer ends of the supplemental extension beams 81, 82 are also connected together by cross bars 34 and blocks 36 are also detachably and adjustably fitted on said supplemental extension beams, as will be understood.

The operation of my improved apparatus is as follows:

Assuming that automobiles have been placed on the extensions 32 and 33 after having previously fitted the blocks 36 to said extensions and that the motor 47 has been started, the pulley 46 transmits movement to the pulley 44 and the gear 48-49 communicates movement to the axle 50. Assuming that the pinion 52 is in gear with the corresponding wheel 54 fixed to the screw 17 said screw will be rotated and the movement will be transmitted to each of the other screws 18, 19, and 20 by means of the chain 60 and sprocket wheels 56, 57, 58, 59, thus causing said screws to move upwardly through the arms 13, 14, 15 and 16 and to move the platform 21 therewith, consequently lifting the beams 22 and 23 together with the extensions 32 and 33 on which the cars B and C are mounted, as indicated in dotted lines in Figure 4 and in full lines in Figure 3. When the desired height is reached such as will enable persons to pass readily under the raised automobiles, the posts 77 illustrated in Figure 13 are employed. Each post consists of a bar forked at the extreme upper end as indicated at 77' to enable it to be secured by a pin passed therethrough and through one of the openings near the outer end of the extension beam. Said bar has joined to its lower end a forked foot 78 which bears on the floor.

To lower the automobiles the hand wheel 66 is fixed to the rod 71, and the latter turned to cause the pinion 52 to be disconnected from the wheel 55, thereby reversing the movement of the lifting screws and causing them to descend.

However, if it is desired only to tilt the automobiles, the posts 77 are not removed. The bolts 32^a are removed, however, so that the bolts 32' form pivots on which the extension beams are free to turn. Hence when

the lifting apparatus is lowered, the extension beams assume an inclined position, together with the automobiles thereon, as shown by dotted lines in Figure 3.

If it is desired to give a rotary movement 70 to the supports which carry the automobiles, the gears 52, 53 are disengaged from the gears 54, 55, and the pinion 41 is caused to gear with the gear 40 fastened to the axle 42 by operating the clutch 64 of the pinion 41 75 by means of its rod 63, which can be done by means of the hand wheel. This causes the shaft 37, together with the pinion 20 to revolve, and said pinion being engaged with the internal gear 19 the turntable ring 10, together with all the lifting mechanism will be revolved, as will be understood.

In case the upward movement of the four screws or posts 17, 18, 19 and 20 because of carelessness or any other reason should not 85 stop at the convenient limit, the stop 72 will come in contact with the cam which forms the top surface of the plate 74 and will communicate a sufficient turning movement to the rod 71 to automatically operate the shifting arms 68, 69 and will hence connect the gear 53 with the wheel 55 and disconnect the pinion 52 from the wheel 54, thereby stopping the apparatus. On descending beyond the convenient limit the stop 73 will 95 slide over the cam of the top border of the plate 74 and will effect a reverse operation of the gears, thereby stopping the descent of the apparatus.

The arms 75 held by the stops 76 prevent 100 all lateral movement which would disarrange the structure while in operation.

The apparatus is also adapted to lift two more automobiles by the employment of the supplemental beams 79 and supplemental extension beams 81, hereinbefore described, and as shown in Figure 2.

In Figure 15 is shown in detail a modified form of the invention for use when it is desired to employ the apparatus simply 110 to raise vehicles but not to communicate rotary movement thereto. In this form of the invention the plates 7, 8 and 10 are omitted and the top frame of the apparatus is reduced to only a circular plate 83 embedded in the wall of the pit, over which plate the lifting screws 86 pass. On the exterior side of plate 84 is an angular groove 83' on which supports 87 are fastened, said supports having bolted thereto a plate 88 115 similar to plate 26, the latter being adapted to support a plate 89 similar to plate 28.

Having thus described my invention, I claim:

1. Lifting apparatus of the class described comprising a turntable element and means to mount and support the same, said mounting means including an internal gear, lifting screws threadedly engaged with said turntable element, a platform connected to 125

said screws to be raised or lowered thereby, a shaft mounted on said platform and having a pinion engaged with said internal gear, and a motor mounted on said platform and geared to said shaft.

2. Lifting apparatus comprising a turntable element, mounting and supporting means therefor including an internal gear, lifting screws threadedly engaged with said turntable element, a platform connected to and carried by said screws, means connecting said screws to cause them to be simultaneously rotated, driving means for said screws, a shaft mounted on the platform and having a pinion engaging said gears, driving means for said shaft geared to said lifting screw driving means, a motor common to said lifting screw driving means and said pinion driving means, and means to en-

gage and disengage said lifting screw driving means and said pinion driving means at will. 20

3. In lifting apparatus of the class described, a supporting element, lifting screws engaged therewith, beams mounted on said lifting screws, extension beams pivotally connected to said beams, and means to support the outer ends of said extension beams to enable them to be inclined when the screws and the beams are lowered. 25

4. In lifting apparatus of the class described, a supporting element, lifting screws engaged therewith, beams mounted on said screws, extension beams connected to the ends of said beams and mounting blocks adjustably seated on said extension beams. 30 35

In witness whereof I affix my signature.

FRANCISCO FABRICIO y DÍAZ.
